UNITED STATES PATENT OFFICE.

FORREST FERGUSON, OF ST. LOUIS, MISSOURI.

NECKTIE-SECURING DEVICE.

SPECIFICATION forming part of Letters Patent No. 757,780, dated April 19, 1904.

Application filed July 11, 1903. Serial No. 165,170. (No model.)

To all whom it may concern:

Be it known that I, FORREST FERGUSON, a citizen of the United States, residing at St. Louis, Missouri, have invented a certain new and useful Improvement in Necktie-Securing Devices, of which the following is a full, clear, and exact description, such as will enable others skilled in the art to which it appertains to make and use the same, reference being had to the accompanying drawings, forming part of this specification, in which—

Figure 1 is a front elevational view of a necktie secured in position by means of my improved fastening means. Fig. 2 is an inverted view, partly broken away and separated, illustrating the several parts of the device; and Fig. 3 is a similar view with the parts in locked position, the socket member being shown in section.

This invention relates, broadly, to improvements in means for securing a necktie in position on the wearer, the object of the invention being to produce a device adapted for that purpose which will be simple, economically manufactured, and which will serve as a secure fastening means for uniting a necktie to a collar-button.

Referring to the drawings, 1 is a base member, of metal or other suitable material, with 30 which is connected an elongated flat shank 2, upon which shank is secured the cap 3, said cap 3 being adapted to fit into and interlock with the socket member 4, which socket member is secured to the necktie-card 5, as shown, by means 35 of the outwardly and backwardly bent claws 6, bearing upon the washer 7, which washer 7 and card 5 are held between said claws and the swelled body portion 8 of the socket 4. The shank 2 is provided with the end portion 40 2^a, which may be of any convenient contour, and between said end portion and the neck portion 2^b there are transverse slots A formed in the edges thereof, which slots project laterally into the metal of the shank. Over the 45 end of the shank is slipped the cap 3, which cap is formed from thin metal in any convenient manner, so as to provide a wide open mouth and a rounded end or apex. After the

cap 3 is placed in position the bead 3^a is formed therein by spinning or by any convenient process, which bead projects inwardly and interlocks with the slots A, before mentioned, whereby the said cap is securely locked in position on the end of said shank, and a collar-button with base member and rigid shank is 55 provided, upon which is secured a separate cap member interlocking therewith, as described.

The socket 4 may be of any convenient form which is provided with spring-holding means adapted to interlock with the cap 3 of the collar-button described; but the style of socket illustrated, which is provided with the annular projecting spring edge portion 4^a, is probably best adapted for the purpose, said spring edge portion interlocking with the said bead 65 3^a to hold the necktie in position upon the collar-button described.

I am aware that minor changes in the construction, arrangement, and combination of the several parts of my device can be made 70 and substituted for those herein shown and described without in the least departing from the nature and principle of my invention.

Having thus described my invention, what I claim as new, and desire to secure by Letters 75 Patent, is—

1. A means for securing neckties in position comprising a socket member adapted to be connected with a tie, in combination with a button member which is provided with a base portion, an elongated flat shank having transverse slotted portions in its respective edges adjacent its upper end, and a separately-formed cap member which is connected with the shank member at its slotted portions, which cap is 85 adapted to interlock with said socket member.

2. A means for securing neckties in position, comprising a socket member connected with a tie, in combination with a button member, said button member comprising a base, an elongated flat shank having slotted portions in its respective edges, and a cap portion having an annular bead engaging the slotted portions of the shank, the said cap being adapted to interlock with said socket member, substantially as 95 described.

3. A collar - button for the purpose described, comprising a base, and an elongated substantially flat shank with cut-away portions in its respective edges, and a cap having an annular bead projecting into said cut - away portions of the shank, substantially as described.

In testimony whereof I hereunto affix my

signature, in the presence of two witnesses,
this 7th day of July, 1903.

FORREST FERGUSON.
